CLAIM

The ornamental design for a faucet, substantially as shown and described.

DESCRIPTION

FIG. 1 is a front view of a faucet, showing my design.

FIG. 2 is a back view of the faucet.

FIG. 3 is a right side view of the faucet.

FIG. 4 is a left side view of the faucet.

FIG. 5 is a top view of the faucet.

FIG. 6 is a bottom view of the faucet; and,

FIG. 7 is a perspective view of the faucet.

The broken lines define the bounds of the claimed design and form no part thereof.
